UNITED STATES PATENT OFFICE.

WILLIAM A. JOHNSON, OF YONKERS, NEW YORK.

RACKET-PRESS.

1,156,363.

Specification of Letters Patent.

Patented Oct. 12, 1915.

Application filed May 28, 1912. Serial No. 700,318.

To all whom it may concern:

Be it known that I, WILLIAM A. JOHNSON, a citizen of the United States, and a resident of Yonkers, county of Westchester, 5 and State of New York, have invented certain new and useful Improvements in Racket-Presses, of which the following is a specification, reference being had to the accompanying drawings, forming a part 10 thereof.

This invention relates to an improvement in presses or frames for holding in shape lawn tennis rackets or the like when not in use, and its object is to provide a simple 15 and efficient device for this purpose which has decided advantages over those heretofore used, and which is an improvement on the press disclosed in my Patent No. 978,455 dated December 13, 1910.

20 I will describe my invention in the following specification and point out the novel features thereof in the appended claims.

In the accompanying drawings, Figure 1 is a plan view of a racket with the press 25 applied thereto. Fig. 2 is a side elevation on an enlarged scale of the press in closed position. Fig. 3 is an enlarged sectional detail of the central clamping screw. Fig. 4 is a similar view of one of the adjustable 30 connections between the ends of the press arms.

Like characters of reference designate corresponding parts in all of the figures.

As illustrated in the drawings, the press 35 comprises two double-bowed truss members each composed of a pair of flat bows 10, 11 and 12, 13 respectively, which are provided centrally with circular enlargements or disks 14, 15, 16 and 17, respectively, said 40 bows preferably tapering slightly from the center toward each end. The bows 11 and 13 are pivotally connected at their centers, preferably by a rivet 18. The bows 10 and 12 are pivotally connected at their centers 45 by a clamping or locking screw 20 which is threaded into the disk 14 and loosely fits a hole 21 provided in the disk 16. The screw 20 is provided with an operating handle 22, and also passes through a washer 24 lying 50 between the disk 16 and the under side of the handle.

By reference to Fig. 2 it will be seen that the bow 10 crosses under the bow 12 at the center and the bow 13 crosses under the bow

11 at the center. Thus the bows 10, 11 constitute an inner double-bowed member and the bows 12, 13 constitute an outer double-bowed member, but the upper sides of the bows 11 and 13 at the points *a*, that is, the lines or surfaces of contact between said bows and the frame 26 of the racket are in the same plane. The opposing ends of each pair of bows 10, 11, and 12, 13 are adjustably and yieldingly connected together; the bows 11 and 13 having a post 30 affixed at 55 each end to their upper surfaces, preferably by being riveted thereto, and a screw 31 passes through each end of each of the bows 10 and 12, and is threaded into the corresponding post 30. A coiled spring 32 surrounds each post 30 and screw 31 and abuts against the inner faces of the opposing ends of the bows. The bows 11, 13, in the present instance constitute what may be termed the fixed clamping member, whereas the bows 70 10, 12 constitute what may be termed the adjustable clamping member, since the ends of bows 10, 12 are adjusted independently by the screws 31 to engage the racket frame, while the ends of bows 11, 13 are in a common, relatively fixed plane.

In use the device in the condition in which it is shown in dotted lines in Fig. 1 is placed over the racket frame 26, then the bows are spread apart into the full line positions with 85 the springs 32 close against the exterior of the frame 26. Next the center or locking screw 20 is tightened to hold the bows in position against the frame. Then the four screws 31 are tightened until there is no 90 play between the bows and the frame. When the press is not in use it may be folded up as indicated by the dotted lines in Fig. 1 so that it occupies but little space. To use the press, after proper adjustment has once been 95 made, it is only necessary to slip it on to the frame, open it squarely against the frame and tighten the center screw 20. After having once adjusted the press no further adjustment is required, unless the press be used 100 upon another racket.

This construction provides a simple, light and rigid frame which when applied to a racket keeps it from warping and occupies so little space that it may be placed with 105 the racket inside of the usual cover or case. The springs 32 tend to spread opposite ends of the frame or press apart so that they

open when the screws 31 are backed out of the posts 30 and also exert sufficient upward pressure upon the heads of the screws to lock them in desired positions.

5. What I claim is:

1. A racket press comprising a pair of double members each having a pair of bows, and adjustable means at their respective ends for setting the bows at a fixed maximum 10 distance apart, said double members being centrally pivoted together and adapted to be swung on their pivots into and out of clamping position on a racket frame, independently of said adjustable means.

15. 2. A racket press comprising an inner double bowed member and an outer double bowed member each composed of a pair of superposed flat bows, the corresponding bows of each pair being pivotally connected 20 at their centers and adapted to be swung on their central pivots into and out of clamping engagement with a racket frame, four corners of said press being located in a common plane, posts affixed to said four corners and 25 means carried by said posts adapted to maintain opposite members of the press in alinement and to adjustably fix the other four corners of the press at predetermined dis-

tances from the first named four corners whereby the press is adapted for use on 30 rackets of varying thicknesses.

3. A racket press comprising an inner double bowed member and an outer double bowed member each composed of a pair of superposed flat bows, two of said bows being 35 pivotally connected at their centers and having posts affixed at their ends, screws carried by the ends of the other two of said bows and threaded into said posts adapted to maintain opposite members of the press 40 in alinement, springs surrounding said posts and screws for holding the opposite members of the press at a fixed distance apart and means for locking said pairs of bows against relative movement about said pivotal connections, whereby the press may be 45 adjusted to accommodate the thickness of the racket and the double bowed members thereof swung into and out of clamping position on a racket frame.

50

In witness whereof, I have hereunto set my hand this 23rd day of May in the year 1912.

WILLIAM A. JOHNSON.
